UNITED STATES PATENT OFFICE.

ROBERT E. WILSON, OF CHICAGO, ILLINOIS, ASSIGNOR TO STANDARD OIL COMPANY, OF WHITING, INDIANA, AND CHICAGO, ILLINOIS, A CORPORATION OF INDIANA.

PUMP CONSTRUCTION.

Application filed December 31, 1923. Serial No. 683,741.

The present invention relates to improvements in pump construction and more particularly to the construction of pumps intended for the dispensing of amounts of liquid, such as gasoline, having related fixed values, for example, volumes having the value of twenty-five cents, fifty cents, seventy-five cents or one dollar, at varying prices per gallon.

10 The invention will be fully understood from the following description, illustrated by the accompanying drawings in which:

Figure 1 is a vertical sectional view through the head of a pump casing embodying the present invention;

Fig. 2 is a partial sectional view on the line 2—2 of Fig. 1;

Fig. 3 is a side elevation of the device shown in Fig. 1; and

20 Fig. 4 is a view of the cam employed in the specific embodiment of the invention illustrated.

In the drawings, the numeral 5 indicates the casing of a pump in which is mounted 25 a suitable type of reciprocating pump, the pump piston rod projecting as indicated at 6. Surmounting the casing 5 is a smaller casing 7, in which the end of the pump piston rod reciprocates and in which is also 30 provided the device constructed in accordance with the present invention for determining the quantities of gasoline or other liquid dispensed by the pump.

Within the casing 7 are mounted a vertical rod 8 and a second vertical rod 9 spaced a short distance therefrom. Slidably mounted upon the rod 8 are the sliding members 10, each of which has projecting lugs 11 forming a yoke. The rod 9 passes through 40 eyes formed in these projecting lugs 11, the sliding members 10 being also slidable thereon. Within the yoke formed by the projecting lugs 11 of each of the sliding members 10 there is pivotally mounted upon the rod 9 a stop lug or member 12. The movement of these lugs on the rod 9 is controlled by means of links 13, of which one is connected to each pivoted lug 12 and extends to the exterior of the casing, and is there provided with a suitable handle 14. The stop lugs 12 are so constructed that, upon being pulled by links 13 into alignment with the rods 8 and 9, they are in the path of the reciprocable piston rod 6. Each of the lugs

12 is provided with an adjusting screw to be 55 engaged by the piston rod and to determine exactly the limit of movement of the latter, thereby controlling the volume of liquid delivered by the pump. By means of the links 13 the stop lugs 12 may be moved 60 out of position to be engaged by the pump rod 6.

As is readily apparent, the sliding members 10 are vertically movable upon the rods 8 and 9, and with them move the stop lugs 65 12. In accordance with the present invention, the positions of the sliding members 10 are so controlled in accordance with the current price of unit volumes of the liquid dispensed, as to correspond to the limiting 70 positions of the pump rod for dispensing volumes of the liquid, for example, gasoline, corresponding to related fixed values, such as given multiples of a fixed unit value, for example, twenty-five cents. Thus, in the 75 form illustrated, four such sliding members 10 may be provided, and the values of the volumes of gasoline or other liquid dispensed on operation of the lugs corresponding to the respective sliding members may 80 be, for example, twenty-five cents, fifty cents, seventy-five cents and a dollar respectively. In the form of construction shown, means are illustrated for setting the positions of all of the sliding members in accordance with current prices of unit volumes 85 of the liquid.

In the form illustrated, a sector 16 is pivoted within the casing near its lower end, with one face opposite the sliding members 90 10 and provided with cam grooves 17 in which are slidably engaged the pins 18 projecting from the sliding members 10. Near its upper end the sector 16 is provided with an externally projecting handle 19, which 95 passes through an arquate slot in the front portion 7^a of the casing 7. An indicating pointer 20 is secured to the handle 19 and markings are provided on the casing 7^a, upon which markings are designated varying 100 prices for unit volumes of the gasoline or other liquid dispensed. In the form illustrated these prices range from sixteen to twenty cents per gallon. The cam grooves in the sector 16 are so formed as to position 105 the sliding members 10 and the corresponding stop lugs 12 properly for the dispensing of volumes of gasoline corresponding to the

total value of twenty-five cents and multiples thereof when the proper stop lugs are engaged by the pump rod in its upper movement. By the operation of the handles 14 and the rod 13, the stop lugs 12 are controlled to dispense the volume of gasoline having the value set by the customer.

It is readily apparent that other mechanical movements may be employed to produce the same results as the sector and cams above specifically referred to, and that the details of the specific construction set forth are not to be regarded as limitations upon the scope of the invention, except in so far as included in the accompanying claims.

I claim:

1. In a liquid dispensing pump, a reciprocable pump rod, a plurality of stops selectively movable into position to be engaged by the pump rod and thereby limit movement of the latter, and means for simultaneously moving the stop members substantially parallel to the line of movement of the pump rod to positions corresponding to the dispensing of volumes of liquids having values which are multiples of a given fixed value in accordance with the price of a unit volume of the liquid.

2. In a pump construction, a reciprocable pump rod, a plurality of vertically movable stop members, means for bringing a selected one of said stops into alinement with the pump rod to limit its movement, and means for simultaneously moving said stop members into positions corresponding to the limiting positions of the pump rod for dispensing total volumes of gasoline having fixed related values at varying prices per unit volume.

3. In a pump construction, a reciprocable pump rod, a vertically movable stop member adapted to be alined with the pump rod to limit its movement and determine the volume of liquid dispensed, a movable indicator member adapted to be set to indicate the current price per unit volume of the liquid, and means controlled by said indicator for vertically moving the stop

member to positions corresponding to total volumes of liquid having identical values. 50

4. In a pump construction, a reciprocable pump rod, a plurality of vertically movable stop members, means for bringing a selected one of said stops into co-operation with the pump rod to limit its movement and determine the volume of liquid dispensed, a movable indicator member adapted to be set to indicate the current price per unit volume of the liquid, and means controlled by said indicator for simultaneously vertically moving the stops to positions corresponding to total volumes of the liquid having identical- 60
ly related values.

5. In a pump construction, a reciprocable pump rod, a plurality of vertically movable stop members, means for bringing a selected one of said stop members into cooperation with the pump rod to limit its movement and determine the volume of liquid dispensed, a cam member having means controlling the vertical positions of said stop members whereby, in all positions of the cam member, the positions of the stop members correspond to total volumes of the liquid having identically related values, and 70 means for moving the cam member to positions corresponding to varying prices per unit volume of the liquid.

6. In a pump construction, a reciprocable pump rod, a plurality of vertically movable stop members, means for bringing a selected one of said stop members into cooperation with the pump rod to limit its movement and determine the volume of liquid dispensed, said stop members having alined 85 projecting pins, a pivotally movable sector member having cam grooves in which said pins are slidably engaged, and means for moving the sector member to positions corresponding to varying prices per unit volume of the liquid, said cam grooves being so constructed that the positions of the stop members correspond at all times to total volumes of the liquid having identically related values.

ROBERT E. WILSON.
